TELEPHONE DUCT

Lyle H. Mathews, Fullerton, Calif., assignor to Under-ground Devices, Inc., Elk Grove Village, Ill.

Filed Nov. 1, 1972, Ser. No. 302,768

Term of patent 14 years

Int. Cl. D13—03; D14—99
U.S. Cl. D26—5 B

FIG. 1 is a top perspective view of a telephone duct showing my new design and looking in the direction of one end thereof; and

FIG. 2 is a bottom perspective view thereof looking in the direction of the other end thereof.

I claim:

The ornamental design for a telephone duct, as shown and described.
